FLUORESCENT LIGHT SAFETY LOCK
REMOVERRobert T. Riker and Joseph H. Molat,
New York, N. Y.

Application December 14, 1945, Serial No. 635,129

3 Claims. (Cl. 294—20)

(Granted under the act of March 3, 1883, as
amended April 30, 1928; 370 O. G. 757)

1

This invention relates in general to a device for removing and replacing distant objects, and in particular to such a device for changing safety locks on fluorescent light fixtures where such fixtures are located in elevated positions or in other positions that are inaccessible to hand operation.

There is at present in commercial use in connection with fluorescent light fixtures a safety lock for preventing the accidental loosening of the fluorescent tube which not only would cause breakage of the tube but might cause damage to surrounding objects and endanger working personnel. Before the fluorescent lamps or tubes can be removed it is necessary to remove the safety lock. It is often desirable to use a lamp changer (such as that described in our copending application, Serial No. 635,130, filed December 14, 1945, which matured into Patent Number 2,504,152 on April 18, 1950) from the floor to remove these tubes rather than to employ stepladders, staging or scaffolds, and in some instances it is impossible to use such rigging because of underlying machinery or other furnishings. Therefore it also is necessary to provide means for removing the safety lock from a remote position.

An object of this invention is to provide an implement, having a long handle that is light in weight and easily manipulated for releasing and removing such safety locks from remotely located fluorescent light fixtures and for replacing such locks.

Further objects and advantages of this invention, as well as its construction, arrangement and operation, are apparent from the following description and claims in connection with the accompanying drawings, in which

Fig. 1 is a side elevation of the device of this invention.

Fig. 2 is a top view of the device of Figure 1.

Fig. 3 is a side elevation of the device showing its relation with respect to a safety lock in a fluorescent light fixture during the removal thereof, and

Fig. 4 is an elevational view looking from the right of Fig. 3;

Fig. 5 is an isometric view showing the device in position to start withdrawal of the pin from the lock;

Fig. 6 is an isometric view showing the device acting upon the lock to release the pin;

Fig. 7 is an isometric view showing the device withdrawing the pin from the lock;

Fig. 8 is an isometric view showing the device inserting the pin in the lock;

2

Fig. 9 is an isometric view showing the device forcing the pin into engagement with the lock.

The safety lock changer comprises a furcated member generally designated 10 made up of two leaves 12 and 14 (Figure 4) resilient material riveted, bolted or otherwise joined together at 16 and bolted or otherwise secured at 18 to a handle 20 of wood or other lightweight material. The leaves 12 and 14 are cut to provide stepped end portions 22 and 24 (Figs. 1 and 3) that are flared slightly at 26 and 28 (Figs. 2 and 4).

Figs. 3 and 4 show the safety lock to which the device of this invention is particularly adaptable. This lock comprises a flat member 30 of resilient material having holes 32 and 34 designed to accommodate the contact pins 35 of a standard fluorescent lamp tube 36. A projecting ear 37 extends from the flat member 30 and is slotted at 38 to receive an L-shaped locking pin 39. Locking pin 39 is provided with a notch 40 into which the projecting ear 37 normally snaps. Once inserted, the locking pin 39 stays in place due to the bearing of the outer extremity of the slot 38 in the notch 40 and prevents any turning movement of the tube 36 by cooperation with the lamp socket (not shown). In order to remove the locking pin 39 the projecting ear 37 is depressed past the notch 40 and at the same time the locking pin is pulled out of the slot 38.

30 An operator standing on the floor centers the pin 39 between the leaves 12 and 14 of the lock changer by means of the flared portions 26 and 28. Upward pressure then forces the device upon the pin 39 with the extending portion 24 forcing 35 projecting ear 37 back past the notch 40. This position is shown in Fig. 3. The lock changer is lowered, and the locking pin 39 is pulled from the fixture, remaining between the leaves 12 and 14. The resiliency of the material of which the lock changer is constructed causes the device to grip the pin 39 sufficiently to enable it to be withdrawn. Optionally, corrugations or teeth are provided upon the internal surface of the leaves 12 and 14 as seen at 29.

45 The operation of withdrawing pin 39 from lock 30 is further shown in Figs. 5 to 7. In Fig. 5, tool 10 is positioned with flared portions 26 below notch 40 of lock ear 37. In Fig. 6, tool 10 is moved upwardly so that flared portions 26 force lock ear 37 upwardly and out of engagement with pin notch 40 to release pin 39. At the same time tool end portions 22 and 24 of leaves 12 and 14 grip the bottom of pin 39. In Fig. 7, tool 10 is moved downwardly with tool end portions 22 and

24 gripping pin 39 to withdraw pin 39 from lock 30.

In replacing the pin 39 it is placed between the leaves 12 and 14 forward of the extending portion 24 so that upon insertion of the pin in the fixture the projecting ear 37 is not pushed down but instead is left free to snap into the notch 40.

The operation of inserting or replacing pin 39 in lock 30 is shown in Figs. 8 and 9. In Fig. 8, tool 10 has been reversed from left to right relative to the position shown in Figs. 5 to 7. The bottom of pin 39 is gripped by tool end portions 22 and 24 of leaves 12 and 14, with tool flared portions 28 below pin notch 40. Pin 39 is inserted into lock slot 38. As shown in Fig. 9, tool 10 is moved upwardly to force pin 39 into lock slot 38 so that lock ear 37 snaps into engagement with pin notch 40. In the inserting operation, flared portions 26 are out of registration with lock ear 37 so that the latter is free to engage pin notch 40.

It requires only a matter of seconds to remove a safety lock in this manner and the fluorescent tube can then be removed by any conventional lamp changer.

It is to be understood that various modifications and changes can be made in this invention without departing from the spirit and scope thereof as set forth in the appended claims.

The invention described herein may be manufactured and used by or for the Government of the United States of America for governmental purposes without the payment of any royalties thereon or therefor.

What is claimed is:

1. A tool comprising a pair of elongated, opposed spring leaves fastened together remote from their opposed ends, said leaves having their opposed ends flared away from each other, each leaf being formed with a first terminal and a second terminal spaced longitudinally beyond the first terminal, said terminals extending transversely and inwardly from opposite edges of a single leaf, the first and second terminals being both longitudinally and transversely offset, and the first terminals of the two leaves being in opposed relation and the second terminals of the two leaves being in opposed relation.

2. A tool comprising a pair of elongated, op-

posed spring leaves fastened together remote from their opposed ends, said leaves having their opposed ends flared away from each other, each leaf being formed with a first terminal and a second terminal spaced longitudinally beyond the first terminal, said terminals extending transversely and inwardly from opposite edges of a single leaf, the first and second terminals being both longitudinally and transversely offset, and the first terminals of the two leaves being in opposed relation and the second terminals of the two leaves being in opposed relation.

15. 3. A tool comprising a pair of elongated, opposed spring leaves fastened together remote from their opposed ends, said leaves having their opposed ends flared away from each other, each leaf being formed with a first terminal and a second terminal spaced longitudinally beyond the first terminal, said terminals extending transversely and inwardly from opposite edges of a single leaf, the first and second terminals being both longitudinally and transversely offset, and the first terminals of the two leaves being in opposed relation and the second terminals of the two leaves being in opposed relation.

20. 4. A tool comprising a pair of elongated, opposed spring leaves fastened together remote from their opposed ends, said leaves having their opposed ends flared away from each other, each leaf being formed with a first terminal and a second terminal spaced longitudinally beyond the first terminal, said terminals extending transversely and inwardly from opposite edges of a single leaf, the first and second terminals being both longitudinally and transversely offset, and the first terminals of the two leaves being in opposed relation and the second terminals of the two leaves being in opposed relation, and opposed teeth formed on the opposed faces of said leaves adjacent the first terminals.

ROBERT T. RIKER.
